UNITED STATES PATENT OFFICE.

FREDERICK L. CHAPMAN, JR., OF CHICAGO, ILLINOIS, ASSIGNOR, BY MESNE ASSIGNMENTS, TO ALEC J. GERRARD, OF CICERO, ILLINOIS.

WIRE-TYING MACHINE.

Application filed October 12, 1922. Serial No. 593,969.

To all whom it may concern:

Be it known that I, FREDERICK L. CHAPMAN, Jr., a citizen of the United States, residing at Chicago, in the county of Cook 5 and State of Illinois, have invented certain new and useful Improvements in a Wire-Tying Machine, of which the following is a specification.

This invention relates to wire-tying machines, and is particularly concerned with the provision of an improved portable machine adapted for efficiently tying together under tension the ends of wires looped around packages of various sizes.

15 The principal object of the invention resides in the provision of a machine of the character described embodying several improved features in the construction and operation of the mechanism for positioning, 20 tensioning, twisting and cutting the wire portions.

While the foregoing statement is indicative of the nature of the present invention, numerous advantageous features of the same will 25 be appreciated upon a further understanding of the machine as described in the following specification and illustrated in the accompanying drawings. One particular embodiment of the invention is set forth for the 30 purpose of exemplification, but it will of course be understood that the invention is capable of incorporation in slightly different structural modifications coming fairly within the scope of the appended claims.

35 In the drawings,

Fig. 1 is a front elevation of the machine, showing it placed upon a package and operatively associated with a wire to be secured under tension about the package;

40 Fig. 2 is a side elevation of the machine; Fig. 3 is a plan view of the same;

Fig. 4 is a vertical section on the line 4—4 of Fig. 1;

45 Fig. 5 is an enlarged fragmentary section on the line 5—5 of Fig. 1; and

Fig. 6 is a diagrammatic side view of one of the fingers 63.

It will be observed, upon a detailed inspection of the several views presented in 50 the drawings, that the machine of this invention is of the so-called portable or hand-tool type adapted to be placed upon the upper surface of the package which is to be wired by the machine. The machine consists primarily of a frame 10, wire-tension-

ing mechanism 11, wire-twisting mechanism 12, and wire-cutting mechanism 13, the wire-tensioning mechanism being associated with the flat base portion 14 of the frame, and the wire-twisting and wire-cutting mechanisms being associated with the upright portion 15 of the frame.

The wire-tensioning mechanism 11 comprises two lever arms 16 which are pivotally mounted at their rear ends 17 to the 60 flat base portion 14. The arms 16 turn upon studs 18 carried by the base portion 14 at corresponding points adjacent the spaced rear corners thereof, and their free ends 19 are adapted, upon actuation, to move arcuately 65 away from each other in a longitudinal plane parallel to the general plane of the flat base portion. Each of the free ends 19 of the arms is provided with wire-gripping means of any approved type, the same being 70 shown in the present exemplification of the invention as a pair of coacting upper and lower spring-pressed jaws 20 slidably mounted in converging guide channels 21. Each pair of jaws 20 is adapted to grip the extremity 22 of one of the two overlapped end portions 23 of a wire looped around a package 24 to be wired, and is provided, adjacent the nose portions of the jaws, with a forwardly spring-pressed plunger 25 which is 75 carried by the arm and projects in the path of movement of the pair of jaws whereby to maintain the same in spaced relation to permit the insertion therebetween of the wire extremity 22 which, upon being inserted, presses the plunger 25 back into an 80 inoperative position. The means for operating the arms 16 to further separate the wire-gripping means and thereby place the looped wire under any desired tension comprises a 85 hand-lever 26 which is secured at its lower end to a stub-shaft 27 journaled in a bracket 28 positioned on the flat portion 14 of the machine frame intermediate the pivot-

studs 18. At a point equidistant to both 90 lever arms 16 the stub-shaft 27 has secured thereto a short lever 29 which pivotally connects at its upper free end with a flat link 30. The link 30 is in turn connected to the lever arms 16 at points spaced from their pivotal 95 axes by rigid rods 31 whereby to constitute with the link 30 and the actuating means therefor a toggle joint for further separating the wire-gripping means. By the employment of a toggle joint in this connec- 100 105 110

tion the slack in the looped wire is speedily taken up and any desired tension easily placed upon the wire with an increasing mechanical leverage which is obviously most 5 advantageous under the circumstances present in the tensioning of a wire looped about a package. In order to prevent accidental return movement of the lever arms 16 upon the hand-lever 26 being released, a locking 10 arrangement is provided which consists of a stationary toothed segment 32 mounted on the base portion 14 of the machine frame concentric with the pivoting axis of the hand-lever, a pawl 33 normally in spring- 15 pressed engagement with the segment, and a plunger 34 extending lengthwise of the hand-lever and adapted, upon being depressed, to trip the pawl out of its locking engagement with the segment.

20 The wire-twisting mechanism 12 comprises primarily a rotatable pinion 35 formed on either side with concentric bosses 36 which are journaled in the upright portion 15 of the machine frame just above 25 the front central part of the flat base portion 14. The pinion and bosses are slotted from end to end, as is usual in wire-tying machines of this type, to receive the overlapped end portions 23 of the wire. In order to permit the insertion of the end portions 23 side by side in the pinion 35, that 30 part of the frame portion 15 encompassing the pinion and its mounting is provided with a horizontally disposed slot 37 extending from the front of the frame portion 15 rearwardly to a point just beyond the axis of the pinion. The means for rotating the pinion consists of a vertically disposed train of intermeshing gears 38, 39 and 40; 35 the uppermost gear being secured to one end of a short shaft 41 on the other end of which is provided an operating hand-crank 42. The ratio of the gears and the length of the hand-lever are such as to 40 effect with ease the twisting of the overlapped wire portions, the twisting pinion in the present embodiment of the invention making four revolutions in a forward and downward direction to three revolutions 45 of the hand-crank in a forward and upward direction. The train of gears mentioned is advantageously encased in a housing formed of two complementary sections 43 which constitute the upright portion 15 of the main frame. A handle 44 is provided at the top of the housing, and serves as a means for steadyng the machine either when the hand-lever 26 is being used in tensioning the wire or when the hand-crank 42 is being used in twisting the wire.

50 In order to insure that the overlapped wire portions 23 remain in the slot of the twisting pinion 35 during its rotation, the bosses 36 on both sides of the pinion turn in bearings formed as sleeves 45 which

project toward the pinion from two spaced hook-shaped members 46 provided with short forwardly and upwardly extending arms 47 connected at their free ends with a horizontal tie-rod 48 by means of which 70 the members 46 and their associated bearing sleeves may be tilted about the axis of the sleeves. The sleeves 45 and members 46 are provided with a forwardly facing horizontal aperture 49 which is adapted, when the members 46 are tilted forwardly, to align with the slot 37 in the frame of the machine, and, when the members are tilted upwardly, to close the slot 37 and prevent movement of the wire portions 43 out of the slot of the twisting pinion 35. This construction is clearly shown in Fig. 5; the members 46 being shown in their open position in full lines, and in their closed position in dotted lines. The members 46 are pressed forwardly into their open position by means of springs 50 acting on guide rods 51 between guide blocks 52 for the rods located on the upright portion 15 of the machine frame and thrust blocks 53 carrying the 90 rods and pivotally attached to the horizontal tie-rod exteriorly of the arms 47. Upon the members 46 being tilted upwardly to their closed position, pivoted catches 54 hook over the tie rod 48 and hold the members in their closed position against return movement. The catches 54 are automatically caused to release the tie-rod 48 to permit the members 46 to return to their open position at the end of the wire-twisting 95 operation when the twisting pinion has made four revolutions. The means for effecting this automatic release includes two cams 55 which are mounted on axial extensions of the shaft 56 on which the gear 38 is mounted. The shaft 56 makes one revolution during the complete twisting operation of the pinion 35, and, just as the twisting is being completed, the cams 55 depress 100 riders 57 on the catches and thereby elevate the catches into positions in which they release the tie-rod 48. One of the guide rods 51 for the springs 50 serves a further purpose as the means for holding a pivotally mounted pawl 58 out of locked engagement 105 with an arcuate recess 59 in a disk 60 on the shaft 41 of the hand-crank 42. The guide rod 51 functions, when the members 46 are in their closed position, to bear upwardly against the weighted end 61 of the pawl and thereby hold the pawl inoperative during the wire-twisting operation wherein the disk 60 is required to make three turns. When the wire-twisting operation is completed the members 46 are released and 110 spring downwardly into their open position, whereby the pawl 58 is released and engages in the arcuate recess 59 in the disk 60. Because, however, of the circumferentially extended shape of the recess 59, the 115

120

125

130

disk 60 is allowed to turn a short distance beyond its position in which the slot in the twisting pinion 35 would be just returning to its original alignment with the slot 37 in the machine frame. This permits a slight additional twist to be imparted to the twisted section of the wire which compensates for the natural reflex of the strained metal of the wire portions and 5 permits the twisted portions to then be withdrawn from the pinion and frame slots without binding when the pinion reverses to its original position with its slot in horizontal alignment with the slot of the machine frame. The amount of additional twist imparted by the pinion 35 is readily adjustable by means of a set-screw 62 which is carried by the pawl 58 and acts against one extremity of the recess 59. 10 The means for preventing the overlapped wire portions 23 from being twisted together in either direction beyond the points desired consists of two forwardly projecting fingers 63 which are located on opposite sides of the wire-twisting pinion at points spaced therefrom. The wire is inserted in the mechanisms of the machine with the wire portions near the extremities 22 placed above the fingers 63 and the wire portions removed 15 from the extremities 22 placed below the fingers, whereby the fingers serve to separate the overlapped wire portions 23 at points spaced from the twisting pinion and prevent intertwisting of the wire portions beyond 20 those points. 25 The wire-cutting mechanism 13 for removing the excess wire at points closely adjacent the ends of the twisted section comprises two cutters 64 which are pivotally mounted to the machine frame at the bases of the fingers 63. The cutters preferably straddle the fingers 63 and, upon being actuated, shear downwardly across the upper edges of the fingers along the sides 30 thereof towards the twisting pinion to cut the excess wire portions away that are gripped in the wire-tensioning jaws 20. The cutters 64 are actuated in their cutting movement by cams 65 which are mounted, like the cams 55, on the shaft 56. The cutters are normally held in their elevated positions by the action of leaf springs 66, and are forced downwardly by the cams 65 to shear the wire portions at the completion of the wire-twisting 35 operation.

The operation of the machine of this invention may be summarized as follows:

The machine is placed upon a package 24 to be wired, one extremity of the wire to be used is gripped in the lefthand pair of jaws 20 and the body of the wire fed over the left-hand finger 63, through the slot in the wire-twisting pinion 35, under the righthand finger 63, passed about the package, then under 40 the lefthand finger 63, again through the

twisting pinion 35, over the righthand finger 63, and into gripped engagement with the righthand pair of jaws 20. The stationary handle 44 at the top of the machine may then be gripped with the right hand and the hand-lever 26 drawn forwardly and upwardly to further separate the lever arms 16 and accordingly place the looped wire under the desired tension, the handle 44 serving to steady the machine against the tendency of the machine to tilt forwardly through the forward and upward movement of the hand-lever 26. Upon the looped wire having received the desired amount of tension, the tie-rod 48, which moves the hook-shaped wire-retaining members 46, is pressed upwardly and backwardly into the closed position of the members 46, the members being then locked in their closed position by the catches 54. As the wire-twisting mechanism is prevented by the locking pawl 58 from commencing its operation until the wire-retaining members have been tilted to their closed position, the wire-portions 23 passing through the twisting pinion are assured of being in their proper positions therein at the commencement of and during the twisting operation. The stationary handle 44 may then be gripped with the left hand and the hand-crank 42 given three revolutions in a forward and upward direction which serves to effect, through the pinion 35, the twisting operation upon the overlapped wire portions 23. At substantially the completion 45 of the wire-twisting operation the catches 54 automatically release the tie-rod 48 and permit the wire-retaining members 46 to return to their open position; the pawl 58 automatically engages in the recess 59 in the disk 60 to limit rotation of the crank handle beyond the desired additional rotation serving to "set" the twisted portion as previously described; and the cutters 64 automatically swing downwardly to sever 50 the wire portions at the extremities of the twisted section, this action of the cutters preferably occurring just before the completion of the wire-twisting mechanism in order to place the cut ends neatly on the under side of the twisted portion. The machine 55 may now be withdrawn rearwardly over the surface of the package from its engagement with the now completed loop of wire.

I claim:

1. In a machine of the character described, wire-twisting mechanism, spaced wire-tensioning members located on opposite sides of the wire-twisting mechanism and adapted to engage with the overlapped end portions of a wire looped around a package, pivoted means to move each of said members arcuately away from the wire-twisting mechanism whereby to place the looped wire under tension in proper association with the wire-twisting mechanism, and separate 120

125

130

- means for operating the wire-twisting mechanism independently of the operation of the wire-tensioning mechanism.
2. In a machine of the character described, wire-twisting mechanism, and wire-tensioning mechanism comprising spaced members adapted to engage with the overlapped end portions of a wire looped around a package, an operating lever, and a toggle connection between the members and the lever for further separating the members upon movement of the lever in one direction.
3. In a machine of the character described, wire-twisting mechanism; and wire-tensioning mechanism comprising spaced pivotally mounted members provided adjacent their free ends with wire-gripping jaws adapted to engage with the overlapped end portions of a wire looped around a package, a pivotally mounted operating lever, and a toggle connection between the members and the lever for further separating the members upon movement of the lever in one direction.
4. In a machine of the character described, wire-twisting mechanism; and wire-tensioning mechanism comprising spaced pivotally mounted members provided adjacent their free ends with wire-gripping jaws adapted to engage with the overlapped end portions of a wire looped around a package, a pivotally mounted operating lever for further separating the members upon movement of the lever in one direction, and means serving to hold the lever against movement in the other direction during the operation of the wire-twisting mechanism.
5. In a machine of the character described, wire-twisting mechanism comprising a slotted pinion adapted to receive two overlapped portions of a looped wire, members disposed on opposite sides of the pinion for preventing the portions of wire from being intertwined at points other than between the members upon rotation of the pinion; and pivoted hook means supporting said pinion interposed between the members for retaining the portions of wire in the slot of the pinion during the rotation of the same.
6. In a machine of the character described, wire-twisting mechanism comprising a slotted pinion adapted to receive two overlapped portions of a looped wire, members disposed on opposite sides of the pinion for preventing the portions of wire from being intertwined at points other than between the members upon rotation of the pinion; hook means supporting said pinion interposed between the members for retaining the portions of wire in the slot of the pinion during the rotation of the same, and means for automatically rendering inoperative said hook means upon the completion of the wire-twisting operation.
7. In a machine of the character described, wire twisting mechanism comprising a slotted pinion adapted to receive two overlapped portions of a looped wire; members disposed on the opposite sides of the pinion for preventing the portions of wire from being intertwined at points other than between the members upon rotation of the pinion; hook means interposed between the members for retaining the portions of wire in the slot of the pinion during the rotation of the same; means for automatically rendering inoperative said hook means upon the completion of the wire twisting operation; and means whereby said hook means serve in their inoperative position to control the operation of the wire twisting mechanism.
8. In a machine of the character described, the combination of a wire twisting mechanism comprising a slotted pinion adapted to receive two overlapping portions of a looped wire; a slotted member rigid with the machine frame and adapted to receive said overlapped wires; pivotally mounted hook means adapted to cooperate with said slotted member and to encompass the portions of wire placed within the pinion, thereby retaining said portions of wire in the pinion during the rotation of the same; and connections by which said hook means control the operation of the twisting pinion.
9. In a machine of the character described, the combination of wire twisting mechanism comprising a slotted pinion adapted to receive two overlapped portions of a looped wire; a pivotally mounted hook means adapted in cooperation with the slotted portion of the machine frame to encompass the portions of wire placed within the pinion, thereby retaining the portions of wire in the pinion during the rotation of the same; means to automatically move said hook means into an inoperative position upon the completion of the wire twisting operation; and connections by which said hook means control the operation of the twisting pinion.
10. In a machine of the character described wire twisting mechanism comprising a slotted pinion adapted to receive two overlapped portions of a looped wire, two spaced pivotally mounted hooks controlling the operation of the twisting mechanism, said hooks adapted in cooperation with an interposed slotted portion of the machine frame to encompass the portions of wire placed within the pinion thereby retaining the portions of wire in the pinion during the rotation of same, and said hooks being automatically moved into inoperative positions upon the completion of the wire-twisting operation.
11. In a machine of the character described, the combination of a frame; a wire

twisting mechanism; hook means for holding said wire in said twisting mechanism; a wire tensioning mechanism; a lever pivotally mounted on the frame for operating one of 5 said mechanisms; a vertically disposed handle carried rigidly by the frame adjacent the upper portion thereof for preventing the frame from tilting about its base upon the operation of said lever; and connections by 10 which said hook means control the operation of the twisting pinion.

12. In a machine of the character described, the combination of a wire twisting mechanism comprising a slotted pinion

adapted to receive two overlapped portions 15 of a looped wire; hook means comprising a longitudinally slotted rotatable sleeve forming a bearing for the pinion and adapted upon rotation to close the outer portion of the slot therein, thereby properly positioning the overlapped wire portions at the commencement of the twisting operation; and connections by which said hook means control the operation of the twisting pinion.

In testimony whereof I have hereunto 20 25 subscribed my name.

FREDERICK L. CHAPMAN, JR.
